UNITED STATES PATENT OFFICE.

JOHN F. O'CONNOR, OF CHICAGO, ILLINOIS, ASSIGNOR TO WILLIAM H. MINER, OF CHAZY, NEW YORK.

RAILWAY DRAFT RIGGING.

Application filed May 6, 1920. Serial No. 379,328.

To all whom it may concern:

Be it known that I, JOHN F. O'CONNOR, a citizen of United States, residing at Chicago, in the county of Cook and State of Illinois, have invented a certain new and useful Improvement in Railway Draft Riggings, of which the following is a full, clear, concise, and exact description, reference being had to the accompanying drawings, forming a part of this specification.

This invention relates to Improvements in railway draft riggings.

One object of the invention is to provide an improved arrangement for a railway draft rigging wherein the assembling, inspection and renewal of parts is greatly facilitated as compared with present arrangements of draft riggings.

More specifically, the object of my invention is to provide a draft rigging arrangement of the horizontal yoke type wherein all the parts of the rigging can either be readily dropped down as an entirety when necessary for replacement of parts or the parts swung down without being disconnected from the underframe to thereby permit inspection.

In the drawing forming a part of this specification, Figure 1 is a vertical longitudinal sectional view of a portion of a railway draft rigging showing my improvements in connection therewith. Figure 2 is a horizontal sectional view of the structure shown in Figure 1 and corresponding to the line 2-2 thereof. And Figures 3 and 4 are vertical transverse sectional views taken on the lines 3-3 and 4-4 respectively of Figure 1.

In said drawings, 10-10 denote channel shaped center or draft sills of a railway car. Mounted between said sills and rigidly secured thereto is what may be termed a combined anchoring and abutment block designated generally by the reference A, said block, in actual practice, preferably constituting a part of the body bolster of the car. A portion of a drawbar is indicated at 11 with which cooperates a horizontal yoke 12, the same being keyed by a coupler key 13.

Also mounted between the draft sills are two stop castings which are preferably integrally formed and combined in a single casting designated by the reference B. Within the casting B and the yoke 12 is mounted the shock absorbing mechanism proper, the same being designated generally

by the reference C. Front and rear followers 14 and 15 are employed in combination with the shock absorbing mechanism. A detachable saddle plate 16 is used, the same being bolted to the flanges of the draft sills as clearly indicated in Figure 3.

In carrying out my invention, the double stop casting B is provided at its rear end with a pair of rearwardly extending spaced perforated heavy lugs 17-17, the same fitting between three spaced forwardly extending lugs 18-18 formed on the casting A. The lugs 17 are rearwardly tapered and the lugs 18 are forwardly tapered as clearly indicated in Figure 1. All of said lugs 17 and 18 and also the draft sills, are provided with alined perforations to accommodate a heavy pivot pin 19 which is removably mounted and adapted to be held against accidental displacement by any suitable means such as the cotters 20-20. With the arrangement shown, it is evident that the casting B is adapted to pivot or swing on the pin 19 in a downward direction upon removal of the saddle plate 16 and taking out of the key 13. Also, by removing the saddle plate 16, key 13 and pin 19, the heavy casting B and parts carried thereby may be dropped down bodily. This provides for easy inspection of the shock absorbing mechanism in the one case and easy renewal or replacement of the parts in the other case.

Said casting B, as heretofore indicated, combines two stop castings designated by the references 21-21. Each of said castings is provided at its forward end with upper and lower spaced front stop shoulders 22 and 23. Each of said stop castings 21 is also formed with a longitudinally extending guiding groove 24 for the corresponding arm of the yoke 12. Said casting B may also be slotted at its rear end as indicated at 25 to accommodate the rear portion of the yoke flush therein so that the rear connecting section of the casting B provides upper and lower stop shoulders 26 and 27 for the rear follower 15. It is evident that the yoke will be supported by the casting B because of the construction heretofore described. To support the shock absorbing mechanism directly from the casting B, the latter is provided with inwardly extending flanges 28-28 along the bottom thereof as clearly indicated in Figure 4 and a connect-

ing bridge piece 29 may be employed as clearly indicated in Figure 1. In this manner the shock absorbing mechanism proper is supported and is removable from the casting B through the open top of the latter.

The draft sills may be reinforced around the slots which accommodate the coupler key 13 by reinforcing plates 30—30 shown most clearly in Figure 2.

10 In the drawings I have shown a well known type of friction shock absorbing mechanism, but it is evident that other types may be employed without departing from the spirit of the invention.

15 In operation, upon inward or buffing movement of the drawbar, the yoke will remain stationary but the shock absorbing mechanism will be actuated against the rear follower 15 which is held by the casting B,

20 the latter in turn being held by the block A either directly or by means of the pin 19 or both. In draft or outward movement of the drawbar, the coupler key 13 will pull the yoke 12 forwardly, thereby compressing

25 the shock absorbing mechanism against the front follower 14 which is held by the stops 22 and 23, the casting B being of course held against outward movement by the pin 19. In this connection, it will be noted that 30 the heavy pin 19 is under quadruple shear and hence can easily be made of sufficient strength to withstand the pulling forces.

The construction shown and described comprises relatively few parts which are 35 easily assembled and are also readily available for inspection or replacement. It will be noted also that the buffing shocks are transmitted entirely to the rear of the mechanism and to the sills through the block A 40 to the body bolster, thereby eliminating tendency of the sills to buckle forwardly of the bolster as in the case of prior types of draft riggings.

I claim:

45 1. In a railway draft rigging the com-

bination with draft sills and a rear abutment block; of a pair of laterally spaced stop castings integrally united at their rear ends and adapted to sustain a shock absorbing means and a draw bar, said castings being spaced apart laterally to permit removal of the shock absorbing mechanism bodily in a vertical direction, means for pivotally anchoring said integrally formed stop castings to said abutment block to swing about a horizontal axis; and a single detachable means for normally separately supporting the forward ends of the stop castings and the draw bar.

2. As an article of manufacture, a stop casting comprising a pair of opposed laterally spaced longitudinally extending cheek pieces, provided at the forward ends with longitudinally extending transversely aligned key receiving perforations; and also provided with horizontal longitudinally extending guide grooves and adapted to accommodate a yoke, front and rear stop shoulders on each cheek piece, a longitudinally extending supporting flange at the 70 bottom of each cheek piece adapted to support and guide the shock absorbing mechanism proper, a web integrally uniting the rear ends of said cheek pieces, and a rearwardly extending pivot lug projecting from 75 said web adapted for pivotal connection with a rear abutment block between the draft sills, said lug being perforated to receive a pivot pin extending transversely of said cheek pieces and stop shoulders, and in 80 alinement with said slots, whereby the casting may be mounted for vertical swinging movement between the draft sills.

In witness that I claim the foregoing I have hereunto subscribed my name this 26th day of Apr., 1920.

JOHN F. O'CONNOR.
